UNITED STATES PATENT OFFICE.

HARRY E. TIDMARSH, OF BANGOR, MAINE, ASSIGNOR OF ONE-HALF TO UNION IRON WORKS, A CORPORATION OF MAINE.

WOOD-CHIPPING APPARATUS.

1,295,388.

Specification of Letters Patent. Patented Feb. 25, 1919.

Application filed January 4, 1919. Serial No. 269,685.

To all whom it may concern:

Be it known that I, HARRY E. TIDMARSH, a citizen of the United States, residing at Bangor, in the county of Penobscot, State of Maine, have invented certain new and useful Improvements in Wood-Chipping Apparatus; and I do hereby declare the following to be a full, clear, and exact description of the invention, such as will enable others skilled in the art to which it appertains to make and use the same.

This invention relates to wood chipping apparatus; and particularly to that type of such apparatus in which the chipping action is effected by means of a plurality of movable knives carried by a rotating wheel or disk and coöperating with a stationary knife mounted on the bed of the apparatus, the wood being delivered to cutting position by an inclined feed chute of suitable form.

In apparatus of that character, it is usual to provide in some way for an adjustment of the bed knife with respect to the cutting wheel, which, in turn, ordinarily entails the use of an additional device for retaining the knife in adjusted position on the bed; and it is also customary to provide a liner, generally in the nature of a plate, which is secured within the chute and fastened against the interior surface thereof to receive the wear occurring at the bottom and outer side of the chute. Such an arrangement, however, is necessarily somewhat complicated and correspondingly expensive, owing to the number of adjusting devices or their equivalents which must be employed; and for the same reason, the setting of the bed knife consumes considerable time, while no provision is ordinarily made for an adjustment of the liner, which is usually removed when badly worn.

The object of this invention is to provide an improved device which will serve the double function of holding the bed knife down against the bed in its adjusted position, and of taking up the wear. According to the preferred form of the invention, the device just referred to consists of a solid block of cast steel which fits in an opening formed by cutting away the portion at the foot of the chute directly overlying the adjacent end of the knife, and which rests directly upon the latter, so that the pressure exerted through it will assist materially in overcoming any tendency of the knife to move out of

place. This block preferably has associated with it a cheek plate which is fastened against the interior surface of the chute, and both said plate and the block have their concave upper faces flush throughout with, 60 and forming continuations of, the said chute surface. These two parts are independently removable from the chute, and the block is capable of adjustment with respect to the adjacent parts to effect its initial positioning, as well as to enable any subsequent changes in position which may become necessary. The bed knife is held reliably in position by the pressure exerted upon it through this block, and also by special clamping devices provided for that purpose, and the parts are so constructed as to permit of adjusting the position of the bed knife initially and moving it from time to time to compensate for wear.

The invention also resides in the construction and mounting of the adjusting devices just mentioned, and it further comprehends the provision of various other improved adjusting devices, notably those associated with the shaft whereon the rotary knife carrier is mounted, to adjust and center the said shaft and carrier, and to take up end thrust on the shaft. Other and further improvements will be set forth and explained as the description of the invention proceeds.

An embodiment of the invention which may be considered for all present purposes as preferred, is disclosed in the accompanying drawings; but it is to be understood that no limitation to the specific details of such disclosure is contemplated, excepting as may necessarily be imposed by the terms of the appended claims. On the contrary, modifications and changes may well be made within the scope of said claims, and parts and features of the invention may be utilized without others, and in other and different environments.

In the said drawings:
Figure 1 is a front elevation of the improved apparatus;

Fig. 2 is a plan view thereof;

Fig. 3 is a transverse vertical section on line 3—3, Fig. 1;

Fig. 4 is an enlarged vertical section on line 4—4, Fig. 2;

Fig. 5 is a transverse vertical section, on the same scale as Fig. 4, taken on line 5—5, Fig. 1;

Fig. 6 is a horizontal section on line 6—6, Fig. 5;

Figs. 7 and 8 are perspective views of the cheek plate and base block, respectively; and Fig. 9 is a plan view of the bed knife.

As shown in the drawings, the apparatus consists primarily of a metal bed 1, co-operating fixed and movable cutting devices 2 and 3, and a chute 4 for delivering the wood into position to be cut. The bed 1 is rectangular in shape, of open or skeleton construction, and supported upon a suitable foundation 5, which provides a pit 6 to receive the chips, the walls of the pit substantially alining with the walls of the bed opening.

Both the fixed and the movable cutting devices are mounted on the bed; and the latter device may, as represented, comprise a set of knives 7, adjustably fitted in seats 8 provided therefor in a movable carrier 9, here shown as in the form of a rotary wheel or disk which is keyed to a centrally-disposed, transverse shaft 10, journaled at its ends in bearings 11 and 12 arranged upon the side members of the bed. This construction, broadly speaking, is the one usually employed in chipping apparatus. Any desired number of knives may be utilized, and they may be mounted and positioned in any manner deemed advisable; and the carrier wheel 9 may have any preferred dimensions and any appropriate structure, none of the features thus far described forming in themselves any part of the actual invention. The wheel shaft 10 carries a driving pulley 13, and both this pulley and the aforesaid wheel 9 project into the pit 6.

Means are provided in connection with the bearings 11 and 12 for effecting an endwise adjustment of the wheel shaft 10, so as to position the wheel and its knives 7 relatively to the fixed cutting device 2, and to retain said wheel in such position, while at the same time taking up end thrust of the shaft. According to the preferred form of the invention, the front bearing box 11, which rests upon the upper face of the front member of the bed, has its lower face recessed as at 14, such recess opening through the outer face of the bearing and having its top wall provided with a seat 15 to receive the projecting upper portion of a bronze nut 16 that is disposed within the recess 14, as shown in Figs. 3 and 4. This nut is mounted on the threaded rear portion of a bolt 17, the front portion of which is rotatably fitted in a bearing opening formed through the upper end of a bracket 18 which is bolted to the bed, endwise movement of said bolt being prevented by means of collars 19 disposed at opposite sides of said opening, or in any other desired manner. The box itself is provided with internal annular grooves 20 to receive the transversely-disposed, cir-

cumferential ribs 21 formed on the shaft end (see Fig. 3); from which it follows that when the adjusting bolt 17 is turned, the shaft, and with it the bearing box, will be slid endwise in one direction or the other, relatively to the chute 4, due to the engagement between the ribs and grooves. The bearing is preferably of the self-lubricating type, and after having been brought to adjusted position in the manner above described, may be fastened in such position by means of a pair of bolts 22, the heads of which are anchored in the bed.

The rear bearing 12, as indicated in Fig. 3, is likewise self-lubricating, and is provided at its outer end with an adjusting screw or bolt 23, the inner end of which is adapted to engage a bronze step or cap 24 and to force the same against the adjacent end of the wheel shaft. Hence, after the initial adjustment of said shaft has been effected by means of the screw 17, the screw 23 is then tightened against the step 24 which, in turn, presses against the shaft and completely prevents any endwise movement thereof, said screw 23 being rotatably fitted in an opening provided for it in the outer end of the bearing and being retained in adjusted position by suitable nuts 25. The bearing as a whole may be secured to the bed in adjusted position by bolts 56, in much the same way as the front bearing 11 is fastened in place by the bolts 22.

The fixed cutting device 2 and the parts directly associated with it, embody the most important features of the invention, as has already been stated, and will now be described. The said cutting device is in the form of a comparatively thick, flat plate or knife, which rests on the upper face of the front member of the bed directly beneath the foot of the feed chute. The latter, which is inclined to the extent required to feed the wood by gravity to the cutting devices in the proper position to be cut thereby, and which may have any desired cross-sectional shape, is likewise mounted on said front member and is provided at its sides with lateral webs 26, the flanged bases 27 of which are bolted to the bed. These webs 26 are formed with rearward extensions 28, which are connected, in turn, by a transverse web 29 depending from the bottom of the chute, all as represented in Figs. 5 and 6.

The knife 2 is slidably fitted between the two side webs 28, the inner faces of which may be undercut at their lower ends as indicated at 30 in Fig. 4, to receive the side edges of the knife, while the cross-web 29 terminates sufficiently far above the bed member to permit the knife to be inserted beneath it, as will be understood. The knife is provided with front and rear pairs of short longitudinal slots 31 and 32, for a purpose presently explained, and with

an intermediate transverse slot 33. The last-mentioned slot is designed to receive the projecting lower portion of a bronze nut 34, which is mounted on an adjusting screw 35; 5 the latter extending loosely through an apertured iron block 36 and being provided with a central collar 37 fitting in an opening or seat formed in said block, whereby it is permitted to rotate freely but is held against 10 endwise movement. Block 36 is fastened to the bed 1 by means of two bolts 38, whose heads are anchored therein and whose stems project upward through the slots 31 and through registering vertical openings in said 15 block; and by virtue of this arrangement rotation of screw 35 will produce an inward or outward movement of the knife across the bed and between the latter and the block. The cross-web 29 is cut away at its center to 20 provide a recess 39, which receives the follower nut 34 and prevents it from turning and working out of its slot 33 in the knife.

The portion of the chute which roofs the space comprised between the cross-web 29 25 and the parts of the side webs 28 directly in rear thereof is removed, thereby providing an open space directly overlying the inner portion of the knife. In place of the part thus removed, there is employed a 30 solid steel block or casting 40, shown in detail in Fig. 8, which fits conformably in, and completely fills, such space, and which has its upper face flush throughout with the interior surface of the chute, and constitutes 35 a virtual continuation of said surface. This block 40 rests directly upon the upper face of the bed knife 2, and, by reason of its weight and the pressure exerted through it by the overlying piece of wood, it assists 40 materially in overcoming any tendency of said knife to become displaced from its adjusted position, the block itself being prevented from moving upward by means of a pair of co-acting shoulders 41 with which 45 the abutting faces of the block and the cross-web 29 are provided. The end face of the said block is also formed with a central opening 42, and with a pair of threaded bolt-holes 43 at opposite sides thereof, the opening 42 registering with, but being slightly smaller than, the web opening 39, so as to receive the end of the adjusting screw 35, and to limit the movement of the nut 34 in that direction. The holes 43 have fitted 50 in them the ends of a pair of parallel adjusting screws 44, which are located at opposite sides of the anchor block 36 and pass loosely through openings 45 formed in the cross-web, said screws being furnished with 55 stop collars 46 to engage the outer face of the cross-web.

It follows, therefore, that by turning the screws 44 in the proper direction, the block 40 can be drawn back firmly to its seat 60 against the cross-web 29 with the shoulders

41 in engagement, and held removably in that position. By this arrangement, the block 40 takes the place of the usual wear plate, or at least of so much of it as would ordinarily overlie the foot of the chute, this 70 function being additional to its previously-explained function of holding down the bed knife 2. However, there may be, and preferably is, employed, besides the wear block, a cheek plate 47, shown in detail in Fig. 7, 75 which fits in a seat or recess provided for it in the interior surface of the chute directly at the side of the wear block and is fastened therein by detachable bolts 48; this cheek plate has its upper face flush with that of 80 the block, as well as with the interior surface of the chute.

The bed knife, when worn at one end, may be removed and reversed to bring its other end into use, for which purpose the 85 slot 33 is disposed exactly centrally of the plate, while the pairs of slots 31 and 32 are positioned symmetrically with respect thereto, so that the bolts 38 may be passed interchangeably through either pair of slots, according as one end or the other of the knife 90 is being used.

I claim as my invention:

1. The combination of a bed, a movable cutter, means for driving the cutter, a knife 95 mounted on the bed for co-action with the cutter, an inclined feed chute secured to the bed above the knife and having its base portion removed, and a block removably fitting in the opening thereby produced and having its upper face flush throughout with, and forming a continuation of, the interior surface of the chute, said block resting directly upon the knife to hold it in place on the bed; substantially as described. 100

2. The combination of a bed, a movable cutter, means for driving the cutter, a knife for co-action with the cutter adjustably fitted upon the upper face of the bed, an inclined feed chute secured to the bed above 110 the knife and having the portion of its base which directly overlies the knife removed to provide an opening at such point, and a solid block removably fitting in said opening and having its upper face flush throughout with, and forming a continuation of, the interior surface of the chute, said block resting directly upon the knife to hold it in adjusted position, and means for positioning the block; substantially as described. 115

3. The combination of a bed, a movable cutter, means for driving the cutter, a knife mounted on the bed in position to co-act with the cutter, an inclined feed chute secured to the bed above the knife and having the portion of its base which directly overlies the knife removed to provide an opening at such point, a block removably fitting in said opening and resting directly upon the knife to hold it in place on the bed, and a cheek 125 plate 130

plate fitting in a seat formed in the interior surface of said chute at the side of the block, said cheek plate and said block having their upper faces flush with each other and with 5 the said chute surface; substantially as described.

4. The combination of a bed, a movable cutter, means for driving the cutter, a knife mounted on the bed in position to co-act 10 with the cutter, an inclined feed chute secured to the bed above the knife, said chute having the portion of its base which directly overlies the knife removed to provide an opening at such point, and also having a de- 15 pending web at the rear of said opening, a block for holding the knife in place removably fitting in said opening and having its upper face flush throughout with the interior surface of the chute, and means ex- 20 tending through said web and engaging the block to hold the block in said opening with its rear wall against the surface of said web; substantially as described.

5. The combination of a bed, a movable 25 cutter, means for driving the cutter, a knife mounted on the bed in position to co-act with the cutter, an inclined feed chute secured to the bed above the knife, a member which is located at the foot of the chute, which rests 30 directly upon the knife to hold the knife in place on the bed and which has its upper face flush with, and forming a continuation of, the interior surface of the chute, and means for adjusting the knife relatively to 35 the cutter and independently of said member; substantially as described.

6. The combination of a bed, a movable cutter thereon, means for driving the cutter,

a knife mounted on the bed in position to co-act with the cutter, an inclined feed chute 40 secured to the bed above the knife, a stationary cheek plate fastened in the chute at the foot thereof, and a movable block resting directly upon the knife to hold it in position on the bed, said block having its upper 45 face flush with the interior surface of the chute; substantially as described.

7. The combination of a bed, a movable cutter thereon, means for driving the cutter, a knife mounted on the bed in position to co-act 50 with the cutter, an inclined feed chute secured to the bed above the knife, a stationary cheek plate fastened in the chute at the foot thereof, a movable block resting directly upon the knife to hold it in place on 55 the bed, the cheek plate and the block having their upper faces flush with each other and with the interior surface of the chute, and separate devices associated with the block and the knife for effecting independent 60 positioning movements thereof; substantially as described.

8. The combination of a bed, a movable cutter thereon, means for driving the cutter, a knife mounted on the bed in position to co-act 65 with the cutter, an inclined feed chute secured to the bed above the knife, and wear-resisting means located at the foot of the chute and comprising a part which rests directly upon the knife to hold it in position 70 and a second part with relation to which and to the knife the first-named part is capable of movement; substantially as described.

In testimony whereof I affix my signature. 75
HARRY E. TIDMARSH.
